(57) **CLAIM**

The ornamental design for a wheel rim, as shown and described.

DESCRIPTION

FIG. 1 is front perspective view of a rim showing my new design;

FIG. 2 is a right side view, enlarged in scale, of the rim of FIG. 1;

FIG. 3 is a front plan view, enlarged in scale, of the rim of FIG. 1;

FIG. 4 is a rear plan view, enlarged in scale, of the rim of FIG. 1; and,

FIG. 5 is a sectional view, taken along line 5—5, as shown in FIG. 3, enlarged in scale, of the rim of FIG. 1.
